UNITED STATES PATENT OFFICE.

WILLIAM A. COURTLAND, OF BROOKLYN, NEW YORK, ASSIGNOR TO AMERICAN PIN COMPANY, OF WATERBURY, CONNECTICUT, A CORPORATION OF CONNECTICUT.

MACHINE FOR FEEDING SAFETY-PIN SHIELDS.

1,141,105.

Specification of Letters Patent. Patented June 1, 1915.

Application filed February 9, 1914. Serial No. 817,654.

To all whom it may concern:

Be it known that I, WILLIAM A. COURTLAND, a citizen of the United States, residing in the borough of Brooklyn, county of 5 Kings, and State of New York, have invented certain new and useful Improvements in Machines for Feeding Safety-Pin Shields, of which the following is a specification.

10 This invention relates to machines for feeding safety pin shields or other articles having an irregular contour. In certain types of machines for feeding safety pin shields to the shield-applying mechanisms 15 of safety pin machines, it has been customary heretofore to arrange the shields after they have been withdrawn from bulk so as to deliver them in predetermined order to the safety pins which are successively presented to have shields applied thereto.

20 The primary object of the present invention is to provide improved means for feeding safety pin shields from bulk in the same predetermined order in which they are delivered to the shield-applying mechanism, thereby rendering it unnecessary to provide apparatus of any character such as is usually interposed between the hopper and shield-applying mechanism. A chute of 25 simple construction and arrangement which merely preserves the predetermined order of arrangement effected by the shield-feeding means, serves to convey the shields from the hopper to the shield-applying mechanism.

30 Certain subsidiary and collateral objects of invention will appear in the specification and be specifically pointed out in the appended claims, reference being had to the accompanying drawings in which my invention 35 is exemplified in some preferred embodiments.

35 In the drawings.—Figure 1 is a front elevation of one embodiment of my invention, parts being broken away and parts shown in 40 section; Fig. 2 is a vertical section normal to the plane of Fig. 1, parts being shown in elevation; Fig. 3 is a fragmentary front elevation of the conveyer ring and contiguous portions of the hopper, parts being broken 45 away and parts shown in section; Fig. 4 is a plan development of the same; Fig. 5 is a vertical section similar to Fig. 2, showing a modification; Fig. 6 is a fragmentary front elevation of the conveyer ring of this 50 modification; Fig. 7 is a plan development 55

of the same; Fig. 8 is a side elevation of the chute employed in this modification, parts being broken away and parts shown in section; Fig. 9 is a section on the line IX—IX, Fig. 8; Fig. 10 is a section on the line X—X, Fig. 8; Fig. 11 is a section on the line XI—XI, Fig. 8; Fig. 12 is a section on the line XII—XII, Fig. 8.

The present invention contemplates an improved construction for machines for feeding safety pin shields such as that disclosed in Patent No. 1,119,823 granted to Gustav E. Harcke on December 8th, 1914. In the Harcke machine, means are provided for feeding shields one by one from bulk, 60 but they are not arranged in the predetermined order in which they are delivered to the shield-applying mechanism until after they have passed over a peculiarly formed chute which automatically arranges the 65 shields so that they all assume the same predetermined order. Such a chute is expensive to manufacture and requires considerable attention in operation.

70 One of the main objects of the present invention is to make it unnecessary to provide special apparatus for reversing the arrangement of shields after they have been separately removed from bulk. Accordingly, a conveyer is provided which delivers the 75 shields to the chute all in the same relative disposition or order with respect to their peculiar contour or form. I preferably accomplish this object by means of an annulus which is provided with pockets which fit the 80 contour of the shields so that said shields must assume a predetermined disposition with respect to the annulus before they can enter the pockets which are all arranged in 85 like order. Thus as the shields are lifted 90 separately from bulk, the relative arrangement of their branches is always the same, so that the chute which conducts said shields to the shield-applying apparatus need only 95 to preserve the predetermined order or arrangement brought about by the conveying annulus.

100 According to the present invention, other parts of the Harcke construction are modified or entirely done away with as will appear in the following description.

105 In the embodiment of my invention shown in Figs. 1 to 4 inclusive, the hopper 1 is provided with a sloping floor 2, a partition 3 being provided to separate said hopper 110

into two compartments. The partition 3 is provided with an opening 4 controlled by a gate or shutter 5 which may be raised or lowered by a handle 6 to regulate the quantity of safety pin shields which are allowed to accumulate in the feed chamber 7. By an inspection of Fig. 2, it will be noted that the bottom walls of the feed chamber 7 converge toward the conveyer or annulus 8, which preferably constitutes a rigid portion of a ring gear 9. As seen in Figs. 3 and 4, the conveyer annulus 8 is provided around its inner periphery with a plurality of pockets or recesses 10 which in the preferred form are adapted to receive safety pin shields with their heavier or, in the example shown, their rounded ends lowermost. From an inspection of Fig. 4, it will be seen that each of the pockets or recesses 10 is made narrower at one edge than the other, their conformation being such as to prevent a safety pin shield entering thereto unless said shield is suitably disposed so that its cross-sectional configuration corresponds exactly with the cross section of the pocket or recess or the opening thereto. As a consequence, the shields 11 will all be arranged in one and the same predetermined order which in the present embodiment is with the longer and heavier branches of the shields to the rear with respect to the direction of rotation of the conveyer annulus 8. Ring gear 9 is rotated by a worm 12 on a spindle 13 which is provided at one end with a pulley 14 receiving power from a belt 15. Mounted on a spindle 16 which is suitably journaled in the front wall of the hopper 1, is a hub 17 from which extend a plurality of yieldable arms 18 which are adapted to agitate the bulk of safety pin shields within the feed chamber 7. Referring now to Figs. 1 and 2, it will be seen that a curved band or plate 19 is arranged above the feed chamber floor on the upward travel side of the conveyer annulus 8, the purpose of which is to prevent the shields from dropping out of the pockets or recesses during the upward movement of the conveyer. The lower end of said shield or plate 19 is deflected inwardly at 20 to remove all possibility of the longer branch of the safety pin shield becoming caught. At the same time, the lower end of shield or plate 19 serves to disengage a second safety pin shield which may have become interlocked with a shield in one of the pockets or recesses 10. Preferably, the shield-retaining plate 19 terminates vertically over the axis about which the pockets or recesses 10 revolve to adapt the shields 11 to be discharged downwardly in predetermined position, arranged all in the same order into the upper end of a chute 21 which conveys the safety pin shields to suitable apparatus (not shown) for applying them to

safety pins. Said chute is made of suitable cross section to maintain the predetermined arrangement of the shields 11 as they drop from the conveyer annulus 8.

In the embodiment of my invention shown 70 in Figs. 5 to 12 inclusive, the parts are essentially similar to those already described with reference to Figs. 1 to 4 inclusive. In this embodiment however, the pockets or recesses 22 are arranged transversely of the 75 conveyer annulus 23 as shown in Figs. 5, 6 and 7. Furthermore, in this embodiment, the chute 24 must be constructed with a twist as indicated in Figs. 8, 9, 10, 11 and 12 so as to bring the shields flatwise to the shield- 80 applying apparatus (not shown). Said chute however, operates to maintain the predetermined presentation and order of the shields dropped from the conveyer annulus 23 in a similar manner to that already referred to in the former embodiment. 85

The operation of my improved machine will now be readily understood and briefly described, is as follows: Safety pin shields are charged in bulk in the receiving chamber of the hopper 1, the supply to feed chamber 7 being regulated by the gate or shutter 5. The bulk in chamber 7 is agitated by the flexible arms 18 and during this agitation, numbers of the safety pin shields 90 will assume the predetermined positions in pockets or recesses 10 as already referred to. As said shields are separately lifted from bulk, and as they begin to reach positions where they would be displaced by gravity, 95 they are engaged by the guard or plate 19 which at the same time serves to dislodge all shields which may have become interlocked with shields in the pockets or recesses. As each of said shields reaches the upper end of 100 the guard plate 19, it drops by gravity into the upper end of the chute which maintains the predetermined presentation of the safety pin shields while conducting them to the apparatus for applying them to the safety 105 pins. 110

Without entering into a discussion of the various modifications and constructions which might be embodied within the broad spirit of my invention as set forth in the 115 appended claims, what I claim is:

1. In a machine for feeding safety pin shields, a conveyer provided with pockets for receiving safety pin shields having branches of different thickness, said pockets 120 being suitably formed to receive said shields endwise only when the same ends are presented thereto, and with said branches in predetermined relative positions corresponding to the relative thickness of said 125 branches.

2. In a machine for feeding safety pin shields of greater width adjacent one end than the other and of greater thickness along one edge than the other, a conveyer 130

provided with pockets suitably formed to hold said shields only when the ends of lesser width are presented to the pockets and only when the edges of lesser thickness are arranged in predetermined relation to said pockets.

3. In a machine for feeding safety pin shields, a hopper, said shields having open and closed ends of different cross sectional areas, the open end of said shield being of greater thickness along one edge than along the other, a conveyer provided with pockets adapted to pass into and out of said hopper, the openings into said pockets being intermediate in size to the cross sectional areas at the open and closed ends respectively of said shields and wider on one side than on the other, said pockets being thereby adapted to accommodate the closed ends only of said shields and then only when the legs of said shields are arranged in a predetermined relation to each other.

4. In a machine for feeding safety pin shields of greater width adjacent one end than adjacent the other end and of greater thickness adjacent one edge than adjacent the other edge thereof, a conveyer provided with pockets suitably formed to hold said shields only when the ends of lesser width are presented toward the pockets and only when the edges of lesser thickness are arranged in predetermined relation to said pockets, and a chute suitably disposed to receive the shields from said conveyer and suitably formed to retain said shields in their arranged relations.

5. In a machine for feeding safety pin shields embodying branches of different sizes, a hopper, a conveyer moving through said hopper, said conveyer being provided with pockets opening upwardly in a portion of the conveyer arranged relatively low in the hopper, the entrances into said pockets being adapted to admit said shields only when the heavier branches are all arranged in the same relative direction.

6. In a machine for feeding safety pin shields, a hopper, said shields each having a closed end and legs of greater lateral extent than said closed end, one of said legs being of greater thickness than the other, a conveyer provided with pockets adapted to pass into and out of said hopper, the openings into said pockets being of less lateral extent than the legs of said shields but of greater lateral extent than the closed end of said shields and narrower at one side than at the other to admit the closed ends only of said shields when the legs are arranged in predetermined relation to each other, and shield receiving means adapted to maintain such predetermined arrangement and to convey said shields away from said pockets.

65 7. In a machine for feeding safety pin

shields which are larger at one end than the other and of greater thickness along one longitudinal edge than the other, a hopper, and a conveyer provided with pockets the entrances into which are contracted toward one edge and intermediate in size to the ends of said shields.

8. In a machine for feeding safety pin shields which are larger at one end than the other and of greater thickness along one longitudinal edge than the other, a hopper, and a conveyer provided with pockets the openings into which are contracted in one direction and intermediate in size to the ends of said shields, said conveyer being suitably constructed and arranged to travel adjacent the floor of said hopper with said pockets opening upwardly to affect the predetermined arrangement of the shields by gravity.

85 9. In a machine for feeding safety pin shields enlarged in cross sectional area toward one end and also enlarged toward one edge, a hopper, an annulus disposed in said hopper with its lower run relatively low therein, said annulus being provided with pockets around its inner face into which said shields fall by gravity, the mouths of said pockets being of suitable size and suitably formed to exclude said shields except when their smaller ends are presented to said pockets and with their larger edges arranged in the same predetermined order.

10. In a machine for feeding safety pin shields, a hopper and a conveyer traveling through said hopper, said conveyer being provided with pockets having entrances suitably tapered to admit safety pin shields only when their edges of different thickness are in a predetermined relation to each other, all of said pockets being arranged in the same relation to the conveyer with respect to the taper of said entrances, and means for receiving the shields from said pockets, said receiving means being adapted to maintain the predetermined arrangement of said shields.

11. In a machine for feeding safety pin shields having legs of unequal thickness, the combination with a hopper for the shields in bulk, of an annulus rotatably mounted and having inwardly presented pockets the openings into which are tapered to adapt said pockets to receive the shields only when presented thereto in a predetermined arrangement of the legs of said shields, said openings being arranged in the same order for all said pockets, and means for rotating said annulus.

12. In a machine for feeding safety pin shields that are enlarged toward one edge, a hopper, an annulus disposed in said hopper with its lower run relatively low therein, said annulus being provided with pockets around its inner face, into which said

shields fall by gravity, the mouths of said pockets being suitably formed to exclude said shields except when their larger edges are arranged in the same predetermined order.

13. In a machine for feeding safety pin shields embodying branches of different sizes, a hopper, a conveyer moving through said hopper, said conveyer being provided 10 with pockets opening upwardly in a por-

tion of the conveyer arranged relatively low in the hopper, the openings into said pockets being adapted to admit said shields endwise and suitably formed to exclude said shields except when the heavier branches are all arranged in the same relative direction. 15
